(57) **CLAIM**

The ornamental design for a roofing material, as shown and described.

DESCRIPTION

FIG. 1 is a top perspective view of an embodiment of a roofing material;

FIG. 2 is a top plan view of the embodiment shown in FIG. 1;

FIG. 3 is a bottom plan view of the embodiment shown in FIG. 1;

FIG. 4 is a left side view of the embodiment shown in FIG. 1;

FIG. 5 is a right side view of the embodiment shown in FIG. 1;

FIG. 6 is a rear view of the embodiment shown in FIG. 1;

FIG. 7 is a front view of the embodiment shown in FIG. 1;

FIG. 8 is another top perspective view of the embodiment shown in FIG. 1;

FIG. 9 is a top perspective view of another embodiment of a roofing material;

FIG. 10 is a top plan view of the embodiment shown in FIG. 9;

FIG. 11 is a bottom plan view of the embodiment shown in FIG. 9;

FIG. 12 is a left side view of the embodiment shown in FIG. 9;

FIG. 13 is a right side view of the embodiment shown in FIG. 9;

FIG. 14 is a rear view of the embodiment shown in FIG. 9;

FIG. 15 is a front view of the embodiment shown in FIG. 9; and,

FIG. 16 is another top perspective view of the embodiment shown in FIG. 9.

The dash-dash broken lines in the figures depict portions of the roofing material that form no part of the claimed design. The dot-dash broken lines represent boundaries of the claim and form no part thereof.

1 Claim, 16 Drawing Sheets
